STOVE

Eugene D. Stirlen, New Haven, Conn., assignor, by
means assignments, to Safety-Fuel Incorporated,
West Cheshire, Conn., a corporation of
Connecticut

Application April 22, 1940, Serial No. 330,875

9 Claims. (CL 126—48)

This invention relates to new and useful improvements in stoves.

One object of the invention comprises inter alia a novel stove construction for the combustion of a solidified fuel and particularly of a solidified petroleum fuel such as gasoline or the like.

Another object of the invention comprises a novel stove construction of increased combustion efficiency.

The invention will be more clearly understood and still further objects thereof will appear from the following description read in conjunction with the drawing, in which:

Fig. 1 is a sectional side elevation of a stove in accordance with the invention;

Fig. 2 is a sectional view on the line 2—2 of Fig. 1;

Fig. 3 is an elevational view partially in section of a fuel container package.

With reference to the drawing, the stove construction is preferably that of a detachable assembly having a base stand 10, an annular fuel container 11 with an open top at 12, and a top unit including a series of flue members substantially coaxially aligned and superimposed on the fuel receptacle.

The annular top edges of the fuel receptacle 11 preferably engage and support an outer flanged annular base disc member 13 and an inner flanged disc member 14, so that these parts engage in fitting relation and be retained substantially as one unit. Flanged discs 13 and 14 are held in position by suitable means, such as strut bars 15, to thereby provide for the free passage of the upward flow of fuel vapors.

Three substantially coaxially aligned upright tubular burner flue members 16, 17, and 18, mounted on the disc members 13 and 14, respectively, form inner, intermediate, and outer chambers 19', 17', and 18'. The flue members are preferably progressively higher from the inner to the outer one. Tubular burner flue members 17 and 18 are provided with a multiple number of air holes 19 and preferably with between fourteen and sixteen holes to the square inch, each hole being of approximately one-sixteenth inch diameter. The burner flue member 16 is preferably provided with air holes, such as the perforations 20. The chamber 18' constitutes substantially an air flue while the chamber 19' is essentially a combustion chamber. Suitable air deflector means, such as the inverted cone deflector plate 21, are mounted in the upper part of the burner assembly so as to overlie the flue 55

18' and chamber 19'. It is essential to the successful operation of the device that the deflector means are spaced a substantial distance away from the top edge of the inner burner flue member 16 so as to provide an air passage over and past this edge, as for instance by means of the spacer bars or the like 22 supporting the deflector 21 in spaced relation above the burner flue members 16 and 17. For best results it is preferable to have the deflector 21 of substantially the same diameter as that of the intermediate flue member 17 so as to leave the combustion chamber 19' substantially unobstructed. It is also of advantage to mount the deflector cone in such manner that its spacing from the top edge of the intermediate burner-flue member 17.

Upon ignition of the fuel in the receptacle 11, fuel vapors will rise through the opening 12 into the combustion chamber 18', where air is admitted to these vapors from both sides by the perforations or air holes 19 in the flue members 17 and 18 respectively. The perforated flue members 17 and 18 thus act as perforated combustion tubes enclosing the combustion chamber 18. Large amounts of air pass upwardly through the air flue 18' to the deflector 21. The inflow of air into the combustion chamber 18 through the air holes 19, together with the air deflected across the top of the burner by the deflector 21, causes an efficient combustion of the fuel vapors and the substantial elimination of smoke and soot.

The base disc 13 may be provided with a convenient handle, such as the handle 24, so that the top portion of the stove construction may be conveniently lifted off the fuel container 11 when it is desired to ignite the vapors and start the stove in operation. When it is desired to extinguish the flame, the top part may be lifted off and a suitable cover may be placed on the fuel container, thereby smothering the flame.

In the preferred embodiment of my invention, the fuel receptacle 11 holding the fuel cake 23 is selected in the form of an annular ring having an air passage, as for instance the circular, central air passage 26, positioned and adapted to serve as an extension of the flue 16' and the unrestricted admission of air thereto.

It will be noted that the fuel receptacle forming part of the stove construction constitutes an easily removable unit, and I prefer to put up the solidified fuel cake in a package which after removal of the cover, such as cover 25 illustrated in Fig. 3, can be fitted to the upper part of the

stove construction and used as the fuel receptacle without the necessity of removing the fuel from the package. Such arrangement has the further advantage that it permits the discarding of the old containers after the fuel is used up and the substitution of a new container, thus avoiding any trouble and difficulty of cleaning parts or disposing of carbonaceous or tarry residues.

The foregoing specific description is for purposes of illustration and not of limitation, and it is therefore my intention that the invention be limited only by the appended claims or their equivalents, wherein I have endeavored to claim broadly all inherent novelty.

I claim:

1. In a stove construction for burning solidified fuel the improvement comprising three substantially coaxially aligned upright tubular burner flue members, the outer and intermediate burner flue members having in their walls a multiple number of air holes and defining a combustion chamber, the inner burner flue member defining an inner air flue and with said intermediate burner flue member an intermediate chamber, means for admitting to said combustion chamber fuel vapors emanating from a vaporizing solidified fuel means for admitting a restricted flow of air to said intermediate chamber adjacent the bottom thereof, and air deflector means overlying the inner air flue and inner burner flue member, said intermediate chamber being substantially open and unobstructed at the end facing said deflector means and said deflector means being positioned to deflect air rising through said inner air flue and being spaced a substantial distance from the top edges of the inner and intermediate burner flue.

2. In a stove construction for burning solidified fuel the improvement comprising three substantially coaxially aligned upright tubular burner flue members, the outer and intermediate burner flue members having in their walls a multiple number of air holes and defining a combustion chamber designed and adapted to be placed in communication with a fuel receptacle for solidified fuel, the inner burner flue member defining an inner air flue and with said intermediate burner flue member an intermediate chamber, means for admitting a restricted flow of air from said inner air flue to said intermediate chamber adjacent the bottom thereof, and an inverted air deflector cone overlying the inner air flue and inner burner flue member and extending to above the intermediate burner flue member, said intermediate chamber being substantially open and unobstructed at the end facing said deflector cone and said deflector cone being positioned to deflect air rising through said inner air flue and being spaced a substantial distance from the top edges of the inner and intermediate burner flue members to provide an air passage over and past said top edges.

3. In a stove construction for burning solidified fuel the improvement in accordance with claim 2, in which said intermediate burner flue member is higher than said inner burner flue member and in which the spacing of said cone from the top edge of the inner burner flue member is greater than the spacing of said cone from the top edge of the intermediate burner flue member.

4. In a stove construction for burning solidified fuel the improvement comprising three substantially coaxially aligned upright tubular burner flue members, the outer and intermediate burner

flue members having in their walls a multiple number of air holes and defining a combustion chamber designed and adapted to be placed in communication with a fuel receptacle for solidified fuel, the inner burner flue member having adjacent its bottom portion a multiple number of perforations, said inner burner flue member defining an inner air flue and with said intermediate burner flue member an intermediate chamber, and an inverted air deflector cone overlying the inner air flue and inner burner flue member and extending to above the intermediate burner flue member, said intermediate chamber being substantially closed at its bottom and substantially open and unobstructed at the end facing said deflector cone and said deflector cone being positioned to deflect air rising through said inner air flue and being spaced a substantial distance from the top edges of the inner and intermediate burner flue members to provide an air passage over and past said top edges, said intermediate burner flue member being higher than said inner burner flue member and the spacing of said cone from the top edge of the inner burner flue member being greater than the spacing of said cone from the top edge of the intermediate burner flue member.

5. In a stove construction for burning solidified fuel the improvement comprising three substantially coaxially aligned upright tubular flue members, the outer and intermediate burner flue members having in their walls a multiple number of air holes, and defining a combustion chamber designed and adapted to be placed in communication with a fuel receptacle for solidified fuel, which receptacle has an inner flue extension, the inner burner flue member having adjacent its bottom portion a multiple number of perforations, said inner burner flue member defining an inner air flue and with said intermediate burner flue member an intermediate chamber having a substantially closed bottom, said inner air flue being positioned and adapted to be brought into registry with said flue extension of said receptacle, said intermediate burner flue member being higher than said inner burner flue member, and an inverted air deflector cone overlying the inner air flue and inner burner flue member and extending to above the intermediate burner flue member said intermediate chamber being substantially open and unobstructed at the end facing said deflector cone and said deflector cone being positioned to deflect air rising through said inner air flue and being spaced a substantial distance from the top edges of the inner and intermediate burner flue members to provide an air passage over and past said top edges, the spacing of said cone from the top edge of the inner burner flue member being greater than the spacing of said cone from the top edge of the intermediate burner flue member.

6. In a stove construction for burning solidified fuel the improvement in accordance with claim 5, in which said outer burner flue member is higher than said intermediate burner flue member.

7. In a stove construction for burning solidified fuel the improvement in accordance with claim 5, in which at least some of the air holes in said inner burner flue member are of larger diameter than said air holes in said intermediate and said outer burner flue member.

8. In a stove construction for burning solidified fuel the improvement in accordance with claim 7, in which at least some of the air holes

in said inner burner flue member are of larger diameter than the air holes in said intermediate and outer burner flue members and in which said outer burner flue member is higher than said intermediate burner flue member.

9. In a stove construction for burning solidified fuel the improvement comprising three substantially coaxially aligned upright tubular flue members, the outer and intermediate burner flue members having in their walls a multiple number of air holes, there being to the square inch substantially from 14 to 16 such air holes of approximately $\frac{1}{8}$ " diameter each, the outer and inner burner flue members defining a combustion chamber designed and adapted to be placed in communication with a fuel receptacle for solidified fuel, which receptacle has an inner flue extension, the inner burner flue member having adjacent its bottom portion a multiple number of perforations at least some of which are of larger diameter than said air holes in said intermediate and outer burner flue members, said inner burner flue member defining an inner air flue and with

said intermediate burner flue member an intermediate chamber having a substantially closed bottom, said inner air flue being positioned and adapted to be brought into registry with said flue extension of said receptacle, said intermediate burner flue member being higher than said inner burner flue member and lower than said outer burner flue member, and an inverted air deflector cone overlying the inner air flue and inner burner flue member and extending to above the intermediate burner flue member said intermediate chamber being substantially open and unobstructed facing said deflector cone and said deflector cone being positioned to deflect air rising through said inner air flue and being spaced a substantial distance from the top edges of the inner and intermediate burner flue members to provide an air passage over and past said top edges, the spacing of said cone from the top edge of the inner burner flue member being greater than the spacing of said cone from the top edge of the intermediate burner flue member.

EUGENE D. STIRLEN.
